To all whom it may concern:

Be it known that I, Neil S. Waterman, a citizen of the United States and a resident of 60 Bonner Street, county of Fairfield, Stamford, State of Connecticut, have invented a new, original, and ornamental Design for a Combination Box and Holder for Stemmed Articles, of which the following is a specification, reference being had to the accompanying drawing, forming a part thereof.

On the drawing:

Figure 1 is a view in perspective of the combination box and holder for stemmed articles;

Figure 2 is a top plan view thereof;

Figure 3 is a front view in elevation of one face; and

Figure 4 is a side view in elevation of one side thereof.

The opposite face and side not shown are identical to the face and side shown.

I claim:

The ornamental design for a combination box and holder for stemmed articles, substantially as shown and described.
